US00D936334S

(12) **United States Design Patent** (10) **Patent No.:** **US D936,334 S**
(45) **Date of Patent:** **** Nov. 23, 2021**

(54) **GARMENT BOTTOM**

(71) Applicant: **Under Armour, Inc.**, Baltimore, MD (US)
(72) Inventors: **Merida Miller**, Baltimore, MD (US);
Nicole Parisi, New York, NY (US);
Elyse Alligood, New York, NY (US);
Jeanne Foley, New York, NY (US)

(73) Assignee: **UNDER ARMOUR, INC.**, Baltimore, MD (US)

(**) Term: **15 Years**

(21) Appl. No.: **29/641,845**

(22) Filed: **Mar. 26, 2018**

Related U.S. Application Data

(63) Continuation of application No. 29/565,726, filed on May 24, 2016, now Pat. No. Des. 816,293.

(57) **CLAIM**

The ornamental design for a garment bottom, as shown and described.

DESCRIPTION

FIG. 1 is a rear perspective view of a garment bottom showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The evenly dashed broken lines in the drawings depict portions of the garment bottom and stitching that form no part of the claim. The dash dot broken lines depict boundaries of the claim that form no part of the claim.

1 Claim, 4 Drawing Sheets
